UNITED STATES PATENT OFFICE

ALBERT C. ACKERMAN, OF BALLSTON SPA, NEW YORK

GLOVE

Application filed May 21, 1930. Serial No. 454,367.

This invention relates to new and useful improvements in gloves and in the method of making the same.

One of the objects of my present invention is to construct a glove which is devoid of the usual finger fourchettes, which may be cheaply made, which will properly fit the hand, and which will retain its shape when used.

In the accompanying drawings:

Figure 1 is a perspective view of a glove constructed in accordance with my invention;

Figure 2 is a rear perspective view thereof;

Figure 3 is a plan view of the back section of the glove;

Figure 4 is a plan view of the front section of the glove;

Figure 5 is a plan view of a combined thumb and wrist strip forming a part of the glove;

Figure 6 is a plan view showing the combined thumb and wrist strip attached to the front section of the glove;

Figure 7 is a sectional view taken on the line 7—7 of Figure 6;

Figure 8 is a plan view of the complete glove immediately following the seaming operation and prior to the glove being turned, and

Figure 9 is a cross-sectional view taken on the line 9—9 of Figure 8.

Referring to the drawings, I have illustrated my improved glove as consisting of three pieces only, a back section A, a front section B and a combined thumb and wrist strip C. It is to be understood that these gloves may be formed of knitted or woven material, or other material if desired.

The back section A includes finger portions 5, 6, 7 and 8 and a wrist portion 9, but does not include a thumb portion.

The front section B includes finger portions 10, 11, 12 and 13, respectively, the latter constituting a fore-finger portion, a wrist portion 14 and a thumb portion 15. The wrist

portion 14 is somewhat narrower than the wrist portion 9 of the back section A, and the thumb portion 15 is disposed in longitudinal alinement with the fore-finger portion 13 and is arranged alongside of the wrist portion 14.

The combined thumb and wrist strip C comprises a thumb portion 16 and a wrist portion 17 which are arranged in alinement, the thumb portion being wider than the wrist portion.

In carrying out my improved method of making a glove in accordance with my invention, I first blank the three pieces A, B and C by means of suitable dies. The thumb portion 16 of the piece C is then superposed on the thumb portion 15 of the section B, and united thereto by a line of stitches 18 which extends around the margin thereof, this line of stitches being continued to unite the adjacent edge of the wrist portion 17 of the piece C with the adjacent edge of the wrist portion 14 of the section B. I then superpose the united sections B and C on the back section A and unite the parts by a marginal line of stitches 19. The glove is then turned inside-out and thus made ready for wear.

The top is preferably finished by hemming the same, although any other suitable finish may be employed if desired.

I claim as my invention:

In a glove, the combination with a back section comprising finger portions and a wrist portion; of a front section comprising finger portions, a thumb portion and a wrist portion, the wrist portion of the front section being narrower than the wrist portion of the back section; and the thumb portion being disposed in longitudinal alinement with the fore-finger portion of the front section; and a combined thumb and wrist strip, the thumb portion of the strip being opposed to the thumb portion of the front section and the wrist portion of the strip being disposed

alongside of the wrist portion of the back section, the combined width of the wrist portion of the front section and the wrist portion of the strip being substantially equal to 5 the wrist portion of the back section whereby to permit flat lying of the front section and the thumb and wrist strip compositely upon the back section, said sections and a strip being united by stitching.

10 In testimony whereof, I have hereunto subscribed my name.

ALBERT C. ACKERMAN.
